ELECTRIC SWITCH

George J. Meuer, Milwaukee, Wis., assignor to
Cutler-Hammer, Inc., Milwaukee, Wis., a Cor-
poration of Delaware

Application January 26, 1931. Serial No. 511,359

16 Claims. (Cl. 200—68)

This invention relates to improvements in electric switches, and the same relates more particularly to electric snap switches of the rotary type.

5 An object of the invention is to generally improve and simplify the details of construction and assembly of the parts of the switch and the manner of operating the same.

10 Another object is to provide stationary and movable switch contacts of novel form, the same being directly supported by the insulating base of the switch.

15 Another object is to provide improved means for effecting actuation of the movable contact of the switch.

20 Another object is to provide means for limiting the switch contactor to oscillating movement between given extreme positions together with means independent of the contactor for limiting the actuating element to oscillating movement of a similar character.

25 Other objects and advantages of the invention will hereinafter appear.

30 The accompanying drawing illustrates certain embodiments of the invention, which will now be described, it being understood that the invention is susceptible of embodiment in other forms without departing from the scope of the appended claims.

35 In the drawing, Figure 1 is a vertical sectional view of a single-pole, or single-circuit-controlling, rotary snap switch constructed in accordance with my invention.

40 Fig. 2 is a top plan view of the switch base shown in Fig. 1, with the stationary and movable contact elements in position.

Fig. 3 is a perspective view, in separated relation, of the switch parts shown in Fig. 1.

45 Fig. 4 is a top plan view of a modified form of switch base having stationary contact and terminal elements arranged to provide a switch of the three-point, or multiple-circuit-controlling, type.

50 Fig. 5 is a fragmentary view similar to Fig. 4, but showing a modified form of wiring terminal elements.

Fig. 6 is a perspective view of the switch contactor and the actuating cam member therefor,—
55 a portion of the contactor being shown in section to illustrate the manner of forming the same.

Figs. 7 and 8 are detail perspective views of the stationary contact and terminal members shown in Fig. 5.

Fig. 9 is a sectional view, on the line 9—9, of the actuating cam member shown in Fig. 3.

Fig. 10 is a fragmentary plan view of the metal cover plate of the switch prior to attachment of the metal bushing thereto, and

Fig. 11 is a perspective view of the combined double-contact and terminal element shown in Fig. 4.

Referring to the drawing, the numeral 15 designates the molded insulating base of the switch. Base 15 is preferably hot molded from a phenol-formaldehyde condensation product, such as that sold commercially under the trade name of "Bakelite". This base is of relatively shallow over-all depth, and the same is provided with a substantially cylindrical central recess 16, the bottom wall of which has a stud or pin 17 formed integrally therewith, said stud having a flat annular shoulder 18 formed thereon and raised slightly above said bottom wall of the recess (Figs. 1 and 3).

Opening to the recess 16 at diametrically opposite sides of the latter are the relatively shallower substantially segmental recesses 19 and 20, the end walls 21 and 22 of which act jointly as limiting stops or abutments for the movable contactor 23 of the switch. Contact 23 preferably comprises a stamping of suitable metal, such as brass, having a substantially circular flat body portion 24 adapted to bear against the shoulder 18 aforementioned, said body portion being provided with an opening as shown to accommodate the stud 17 whereby the latter acts as a pivotal support for the former. Contact 23 is provided with upwardly offset diametrically opposed arms the end portions 25 and 26 of which are bent as shown to provide convex lower contact surfaces. The upwardly converging pairs of inclined cam surfaces 27 and 28 on contactor 23 are adapted to merge at the lower ends thereof with the flat portion 24 of the contactor.

Extending inwardly from diagonally opposite corners of the base 15 are a pair of relatively narrow tortuous recesses 29 and 30, the inner ends of which respectively coincide with the segmental recesses 20 and 19. The recesses 29 and 30 are provided with intermediate branches or extensions 29^a and 30^a to facilitate internal wiring of the switch when combined contact and terminal members of the type shown in Fig. 8 are employed, as described hereinafter with reference to Fig. 5. Recesses 29 and 30 open through the end walls of base 15 as shown at 29^b and 30^b to accommodate the insulated wires when internal wiring is provided for, and relatively deeper and relatively narrower slots 29^c and 30^c are provided to accommodate the outwardly extending terminal portions of the one-piece combined contact and terminal members 31 and 32 best illustrated in Figs. 2 and 3.

Members 31 and 32 preferably consist of sheet metal punchings bent as illustrated to snugly fit within the recesses 29 and 30,—the inner edge portions of said members being inclined to the horizontal to provide contact surfaces 31^a and 32^a.

- for cooperative engagement by the end portions 26 and 25, respectively, of the contactor 23. Adjacent to surfaces 31^a, 32^a are the vertical abutment edges 31^b, 32^b—the upper horizontal edges 31^c, 32^c of said members being located in substantially flush relation to the upper surface of base 15 when the parts are in assembled relation. The outer ends of members 31 and 32 may be provided with openings 31^d, 32^d by means of which the bared ends of the terminal wires (not shown) may be looped, twisted and soldered or otherwise rigidly attached thereto. By providing one or more sharp-pointed bosses or projections 31^e, 32^e upon members 31, 32 the latter may be wedged tightly within the respective recesses 29 and 30 to insure rigid positioning thereof when assembled in the base.
- Base 15 may be provided with cavities such as 33, 34 without unduly reducing the strength of the molded piece, while at the same time minimizing the amount of insulating material required, and the weight of the piece, with consequent reduction in cost of manufacture and shipment of the articles.
- 25 Adapted to cooperatively engage contacts 23 is an actuating cam member 35 of substantially channel-shape, the bottom portion of which is provided at opposite ends thereof with downwardly converging inclined cam surfaces 35^a, 35^b—said bottom portion being upwardly offset, as indicated at 35^c and provided with an opening 35^d to accommodate the insulating pivot pin or spindle 17 aforementioned. Member 35 is preferably formed of steel.
- 30 35 Adapted to seat within the cam member 35 for driving of the latter is a flat punched plate 36 of insulating material, such as fiber. Plate 36 is preferably of inverted Y-shape, as shown—the notch 36^a therein being adapted to accommodate or straddle the pin 17. The portion 36^b of plate 36 is preferably of a width substantially equal to the diameter of a cylindrical metal shaft 37, said shaft being diametrically slotted, as indicated at 37^a to accommodate said portion 36^b of plate 36. Shaft 37 is provided with a bore or cavity 37^b to receive the reduced upper end 36^c of plate 36, said end being further reduced, as shown at 36^d to fit within the lower end of a spiral compression spring 38 located within said cavity.
- 35 40 45 50 Struck outwardly from the lower end of shaft 37 are two or more lugs 37^c, 37^d which are adapted to limit the upward displacement of shaft 37 with respect to the externally threaded hollow metal bushing 39 within which said shaft is adapted to bear. Bushing 39 is rigidly attached to a metal cover plate 40, as by spinning an end flange 39^a (Fig. 1) of the former over the lower face of the latter. As shown in Fig. 10, the edge of the opening 40^a in cover plate 40 is preferably notched or serrated, as indicated at 40^b to insure against turning of these parts relatively to each other after the spinning operation. Cover plate 40 is preferably provided with integral lugs 40^c and 40^d which are bent over shoulders formed by recesses 41 and 42 provided at opposite ends of base 15—said lugs being reduced in width as indicated at 40^e and 40^f to facilitate such bending, while providing for a fairly snug fit of said lugs within said recesses.
- 55 60 65 70 75 Interposed between the metal cover plate 40 and the top surface of base 15 is a thin punched plate 43 of insulating material, which acts as additional means to retain the contact and terminal members 31 and 32 in position while insuring against contact of the latter with said cover plate

40. Insulating plate 40 is provided with a pair of segmental openings 43^a, 43^b which communicate with each other, the diagonally related pairs of end walls of said openings being located in parallel planes spaced sufficiently from each other to accommodate the thickness of the plate 36. Said end walls thus cooperate in diagonally related pairs to engage the portion 36^b of plate 36 and thus limit the latter to oscillatory movement within a given range.

Assuming that the contactor 23 is limited to oscillatory movement within a range of approximately sixty degrees, the plate 36 would preferably be limited by the end walls of the segmental openings 43^a, 43^b to movement within a range of approximately ninety degrees, so that movement of the cam member 35 over the high points of the cam surfaces on the contactor will be insured upon movement of plate 36 to each of its extreme positions alternately. Inasmuch as the coiled spring 38 acts to constantly press the cam member 35 into engagement with contactor 23, snap movement of the latter from each extreme position to the other is insured.

The switch as shown is adapted for one-hole 100 mounting upon a suitable panel or other support, the usual nuts 44 and 45 being preferably employed for adjustment with respect to panels or supports of different thicknesses. After the switch is attached to the support an insulating 105 knob or handle 46 may be secured thereto, as by means of the set screw 47. As will be understood, the exposed portion of shaft 37 may itself be milled, grooved or otherwise roughened to serve as a handle, inasmuch as said shaft is 110 properly insulated from the stationary and movable contacts of the switch. Also obviously the shaft 37 might be molded or otherwise formed from insulating material—a suitable shoulder or abutments being formed thereon to perform the 115 function of lugs 37^c, 37^d.

The insulating base 48 shown in Figs. 4 and 5 is in general like the base 15 aforescribed. However, base 48 is provided at the four corners thereof with the relatively narrow tortuous recesses 49, 50, 51 and 52—the recesses 50 and 51 being connected, as shown at 53 to accommodate the portion 54^a of a combined double-contact and terminal member 54 (Figs. 4 and 11), the inclined edge contact surfaces 54^b and 54^c being arranged at an angle to each other to lie in the path of the oscillating contactor of the switch. The right-hand contact and terminal member 55 may be identical with the member 31 shown in Figs. 2 and 3, and the member 56 may be formed from the same blank for assembly at the left-hand side of the switch base.

The recess 16 and stud 17 in Figs. 4 and 5 are like the corresponding parts in the other figures of the drawing. With the stationary contacts arranged as shown in Figs. 4 and 5, the device is adapted to function as a three-point, or multiple-circuit-controlling, switch.

In the arrangement shown in Fig. 5 the switch may be wired internally of base 48 after the stationary contact and terminal members are in position. Thus two of the combined contact and terminal members 57 will be inserted in the recesses at one side of the base, and the combined double-contact and terminal member 58 will be inserted in the connected recesses at the other side of the base. These contact and terminal members 57 and 58 are shown in detail in Figs. 7 and 8—the same being respectively provided with angularly extending notches 57^a and 58^a in the

upper edges of the terminal portions thereof. Thus with the members in position the bared ends of insulated wires, such as 59 and 60 are inserted into the branches or extensions 49^a, 50^a of the recesses 49, 50, and said bared end portions are then bent into the respective notches 57^a, 58^a and snubbed against the walls thereof. A small amount of solder may then be placed upon the adjacent portions of the wires and said members 10 to insure proper electrical connection therebetween.

As will be apparent, the base 48 may be employed in constructing a single pole switch of the character illustrated in Figs. 1, 2 and 3; and 15 the contact and wiring terminal members for internal or external wiring may be employed selectively as desired.

As best illustrated in Fig. 6, upon a predetermined degree of clockwise movement of the 20 spring pressed cam member 35 the latter rides over the high points or ridges of the cam surfaces 27, 28 on contactor 23 whereupon snap movement of the latter in a counter-clockwise direction to one extreme position is effected. Thereafter a 25 corresponding degree of counterclockwise movement of cam member 35 effects snap movement of contactor 23 in a clockwise direction to its opposite extreme position.

Suitable means may be associated with the 30 shaft 37 and the supporting panel for the single-pole switch illustrated in Figs. 1, 2 and 3 to indicate the "on" and the "off" positions thereof.

What I claim as new and desire to secure by Letters Patent is:

35 1. In an electric switch, in combination, a molded insulating base having a centrally located cylindrical recess and segmental recesses on diametrically opposite sides of said central recess and opening thereto, said segmental recesses having vertical notches formed therein, a plurality of punched sheet metal contact members seated edgewise within the respective notches, a stamped sheet metal contactor the body portion of which is located within said central recess and the arm portions of which are oscillatable within said 40 segmental recesses for movement of said arm portions into and out of engagement with said contact members, and means including a spring 45 pressed cam for effecting movements of said contactor with a snap action.

2. In an electric switch, in combination, a molded insulating base having a substantially cylindrical recess, a stamped sheet metal contactor having its body portion rotatably seated 55 within said recess and having arm portions extending radially beyond said recess, a plurality of punched sheet metal contact members seated edgewise within correspondingly shaped recesses in said base and having portions thereof located 60 in the path of movement of said arms, means including said contact members for limiting said contactor to oscillatory movement within a given range, said contactor having double-inclined cam surfaces formed thereon, a cam member spring- 65 pressed into cooperative engagement with said contactor, and means comprising a cover member for limiting said cam member to oscillatory movement within a given range.

3. In a rotary electric snap switch, in combination, a molded insulating base, and a flat punched insulating cover plate therefor, said cover plate having a pair of diametrically opposed segmental openings communicating with each other, for the purpose set forth.

70 4. In an electric snap switch, in combination,

a shallow molded insulating base, punched sheet metal contact and wiring terminal members seated edgewise within correspondingly shaped recesses in said base and having portions thereof extending flush with the upper surface of said base, a flat punched insulating cover plate adapted to retain said contact and terminal members in assembled relation to said base, a pin formed integrally with said base, a stamped sheet metal contactor pivotally supported by said pin, said contactor having a plurality of pairs of upwardly converging inclined cam surfaces formed thereon, an actuating element having downwardly converging inclined cam surfaces formed thereon for cooperation with the cam surfaces aforementioned, a hollow shaft telescopically engaging said actuating element and interlocked with the latter against rotation relatively thereto, and means on said insulating cover plate for limiting said actuating element to oscillatory movement within a predetermined range.

80 5. In an electric snap switch, in combination, a shallow molded insulating base, punched sheet metal contact and wiring terminal members seated edgewise within correspondingly shaped recesses in said base and having portions thereof extending flush with the upper surface of said base, a flat punched insulating cover plate adapted to retain said contact and terminal members in assembled relation to said base, a pin formed integrally with said base, a stamped sheet metal contactor pivotally supported by said pin, said contactor having a plurality of pairs of upwardly converging inclined cam surfaces formed thereon, an actuating element having downwardly converging inclined cam surfaces formed thereon for cooperation with the cam surfaces aforementioned, a hollow shaft telescopically engaging said actuating element and interlocked with the latter against rotation relatively thereto, and means on said insulating cover plate for limiting said actuating element to oscillatory movement within a predetermined range.

- a stamped sheet metal contactor having a flat intermediate portion provided with a bearing opening, diametrically opposed arms offset upwardly from said intermediate portion, the outer ends 5 of said arms being bent to provide lower surfaces of convex form, the adjacent inner portions of said arms each having upwardly converged inclined cam surfaces formed thereon, a channel-shaped sheet metal member having opposite end 10 portions thereof provided with downwardly converged inclined cam surfaces for cooperation with the cam surfaces on said contactor, a flat punched insulating member having driving engagement with said channel shaped member, an operating shaft having telescopic driving engagement with said insulating member, and a coiled compression spring interposed between 15 said shaft and said insulating member.
9. In an electric snap switch, in combination, 20 a stamped sheet metal contactor having a flat intermediate portion provided with a bearing opening, diametrically opposed arms offset upwardly from said intermediate portion, the outer ends of said arms being bent to provide lower surfaces of convex form, the adjacent inner portions 25 of said arms each having upwardly converged inclined cam surfaces formed thereon, a channel-shaped sheet metal member having opposite end portions thereof provided with 30 downwardly converged inclined cam surfaces for cooperation with the cam surfaces on said contactor, a flat punched insulating member having driving engagement with said channel shaped member, an operating shaft having telescopic 35 driving engagement with said insulating member, a coiled compression spring interposed between said shaft and said insulating member, an insulating base having abutments formed integrally therewith to limit said contactor to oscillatory movement within a predetermined range, and additional means associated with said base 40 to limit said insulating member to oscillatory movement within a similar but slightly greater range.
45. 10. A combined stationary contact and terminal member for electric snap switches, comprising a sheet metal member adapted for wedge mounting within a suitably recessed base, said member having an inclined edge portion providing a contact surface and an integral vertical abutment shoulder adjacent thereto, and means 50 on said member to provide for attachment of a terminal wire thereto.
11. A one-piece combined contact and terminal element for electric snap switches, comprising a punched sheet metal member adapted for wedge mounting within a suitably recessed insulating base, said member having an inclined edge portion providing a contact surface and a vertical edge portion abutting said contact surface, and said member having a notch formed 55 in another edge portion thereof to provide for snubbing attachment of a terminal wire thereto.
12. In combination, a molded insulating base 60 having a relatively narrow recess formed therein, a substantially non-resilient sheet metal contact member having a portion of single thickness adapted to seat edgewise within said recess and between the parallel walls of the latter, said portion of said member having a laterally extending cone-shaped boss formed thereon to bite 65 into one of the flat side walls of said recess to thereby provide for a drive fit of said member within said recess, and said member having an angled contact edge portion extending beyond said recess, said contact edge portion being adapted for engagement by a movable contactor 70 of suitable form.
13. In an electric switch, in combination, a molded insulating base having a relatively narrow vertically extending recess formed therein, a punched sheet metal member having a drive fit edgewise within said recess, said member having an inclined edge portion at one end adapted to provide a contact surface, said member having a notch adjacent to the other end thereof, and said base having a relatively small recess adjacent to said notch whereby a wire terminal may be inserted in said last mentioned recess and snubbed against the walls of said notch to permit wiring of said member after attachment thereof to the base.
14. A one-piece combined multiple contact and wiring terminal member for electric snap switches, comprising a metal punching having an intermediate relatively narrow portion and upwardly inclined edge contact portions adjacent thereto and vertical abutment edge portions adjacent to said contact portions, said contact portions being respectively located in vertical planes converging toward said intermediate portion, and means integral with said punching to provide for attachment of a terminal wire thereto.
15. In an electric switch, in combination, a molded insulating base having a substantially cylindrical recess, a stamped sheet metal contactor having its body portion rotatably seated within said recess and having arm portions extending radially beyond said recess, a plurality of punched sheet metal contact members seated edgewise within correspondingly shaped recesses in said base and having edge portions thereof located in the path of movement of said arms, means including said contact members for limiting said contactor to oscillatory movement within a given range, said contactor having double-inclined cam surfaces formed thereon, a cam member spring-biased into cooperative engagement with said contactor, and means for limiting said cam member to oscillatory movement within a given range.
16. In an electric snap switch, in combination, a shallow molded insulating base, punched sheet metal contact and wiring terminal members seated edgewise within correspondingly shaped recesses in said base and having portions thereof extending flush with the upper surface 130 of said base, a flat punched insulating cover plate adapted to retain said contact and terminal members in assembled relation to said base, a pin extending upwardly at right angles to said base, a stamped sheet metal contactor pivotally supported by said pin, said contactor having a plurality of pairs of upwardly converging inclined cam surfaces formed thereon, an actuating element having downwardly converging inclined cam surfaces formed thereon for cooperation with the cam surfaces aforementioned, a hollow shaft telescopically engaging said actuating element and interlocked with the latter against rotation relatively thereto, and means for limiting said actuating element to oscillatory movement within a predetermined range.

GEORGE J. MEUER.
